To all whom it may concern:

Be it known that I, DAVID McNAIR, of Boston, in the county of Suffolk and State of Massachusetts, have invented a new and original Design for Carpets, of which the following is a specification.

The nature of my design is fully shown in the accompanying photographic illustration, forming a part of this specification.

10 The design is composed of the diagonal figures A, arranged in diagonal rows, each figure being substantially rectangular, but composed of two divisions, one of which is somewhat wider than the other; the rectangular figures 15 B, each overlapped by the corners of three figures, A; the light circular figures C, each overlapping one of the figures B and overlapped

by a corner of one of the figures A and ornamented by a diagonal band, and the dark circular figures D, overlapping the figures A B 20 and ornamented by bands extending longitudinally of the piece.

I claim—

The design for a carpet, substantially as shown and described. 25
In testimony whereof I have signed my name to this specification, in the presence of two subscribing witnesses, this 1st day of November, A. D. 1880.
